(57) **CLAIM**

The ornamental design for a biometric ring wearable device, as shown and described.

DESCRIPTION

FIG. 1 is a top-front perspective view of the biometric ring wearable device, showing our new design;

FIG. 2 is a front view of the design illustrated in FIG. 1, the rear view being a mirror image thereof, and

FIG. 3 is a right side view of the design illustrated in FIG. 1, the left side view being a mirror image thereof;

FIG. 4 is a top view of the design illustrated in FIG. 1; and,

FIG. 5 is a bottom view of the design illustrated in FIG. 1. The broken lines in the drawings are for the purpose of illustrating unclaimed portions of the biometric ring wearable device and form no part of the claimed design.
